UNITED STATES PATENT OFFICE.

JAMES EDWARD BENNETT, OF MOMENCE, ILLINOIS.

LOCOMOTIVE.

1,151,240.

Specification of Letters Patent. Patented Aug. 24, 1915.

Application filed June 4 1913. Serial No. 772,019.

To all whom it may concern:

Be it known that I, JAMES EDWARD BENNETT, a citizen of the United States of America, and a resident of Momence, in the county of Kankakee and State of Illinois, have invented certain new and useful Improvements in Locomotives, of which the following is a description, reference being had to the accompanying drawings, forming 10 a part of this specification.

My invention relates to locomotives having a plurality of engine units operated from the same location and the object of my invention is to produce a locomotive 15 comprising a boiler of sufficient capacity to furnish steam for several independent sets of engine gear, mechanism for simultaneously operating the several sets of engine gear, and means for conserving the use of 20 the power produced by the boiler.

In brief, my improvements comprise an improved boiler construction having a double shell, double shell steam domes, and improved means for collecting and disbursing 25 the dry steam; a mounting for the boiler and the engines, comprising a plurality of trucks, properly articulated; and a compensating and spring supporting means for the plurality of trucks, the boiler and fire 30 box.

In the drawings, Figure 1 is a side elevation of a locomotive constructed in accordance with my invention, the casing of the boiler being broken away to disclose the 35 interior construction of the steam generating apparatus; Fig. 2 is a side elevation of a rear locomotive frame, showing the arrangement for spring supporting the trucks, fire box and boiler at this part of the locomotive; Fig. 3 is a plan view of the link 40 movement for one frame of engines; Fig. 4 is a side view of the left link movement from the inside; Fig. 5 is a front view of a pony truck, with a center pin in a swinging 45 drop brace; Fig. 6 is a side view of the connecting, and driving rods for one engine; Fig. 7 is a side view of the link, link block and valve rod, for one engine; Fig. 8 is a side view of a companion to that shown in 50 Fig. 7; Fig. 9 is a cross section of the link block; Fig. 10 is a rear view of the ash box which is fast to the fire box, showing how the walls are fastened by stay bolts, and the water legs, the means for dropping ashes not being shown; Fig. 11 is a longitudinal section of the engine cylinder and valve cas-

ing, showing the valve and piston arrangement.

1 is a boiler, of sufficiently large size to supply steam to several sets of engines. 60

2 is the casing, 3 is the smoke box, and 4 is the fire box (Figs. 1 and 10) the fire door and grate not being shown.

5 are the stay bolts securing boiler and fire box in spaced relation, 6 are the water legs, 7 is the ash box, (Figs. 2 and 10) bolted to the fire box 4, 8 the grate turner, 9 the dry steam domes (Fig. 1), 10 the dome rings, 11 the dome caps, 12 the dome bases, 13 the dome casings, 14 the dome covers, the construction affording a double casting or jacket for the dry steam within the domes. 70

15 is a throttle valve to let steam into the valve box 16, 17 is a throttle valve pipe, and 75 18 an elbow; the pipe 17 and elbow 18 connecting with the main dry steam pipe 24, 19 is the throttle valve stem fast to the throttle valve cranks 20, mounted between lugs on pipe 17 and operating throttle valve 80 rod 21. The rod 19 is packed with a stuffing box or gland 22 where it passes through the rear end of the boiler and is provided with a suitable lever in the cab 23.

The main dry steam pipe 24 communicates 85 with down pipes 25, connecting pipes 26, and supply pipes 27 passing through the arches 28 and the casing pipe 112, whereby steam can be brought to the steam chests 29 of the engines 30. 90

Pipes 31 convey steam from one to the other side of the boiler and pipes 32 exhaust steam through nozzle 33 into the spark dropper pipe 34 above the stack 35, whence it escapes with the sparks and cinders 95 through the catcher 38, the heavier particles falling to the ground.

36 is the nest of boiler tubes or flues, these being larger at the forward end 37 and smaller at the after end, so as to create a 100 stronger draft for a long boiler.

39 are oil holes or cups to lubricate the parts in the steam or valve chest 29. The other and usual oiling means for the several parts of the locomotive are purposely omitted. 105

A suction pump 40, without and adjacent the cab, draws water from the tender 41, through pipes 42 into the boiler 1.

a is a waste pipe.

Air pump 43, through pipes 44, furnishes 110 tanks 45 with compressed air for brakes, etc.

Steam dome 46 supplies steam for whistle.

47 and 48 are gages for the exhaust of surplus steam.

49 is the bell and 50 is the sand box.

51 is the headlight.

5 The boiler 1 rests on arches 28 supported on the frames 52, and on platform 53 of the pony truck, which is also in turn supported on a frame 52. Post hangers 54, support the rocking springs 55 and through them 10 and posts 56 cushion and support the frames 52. Fire box 4 is spring supported on brace 57 and swinging bars 58, supported by the center post hangers 54 and counterbalanced by and supported on frame 52 through 15 swinging dippers 59 holding springs 60. Post hangers 54 rest on boxings 61 mounted in the spaces 62 between depending paired frame posts 52' the spaces being closed below by plates 63 and the boxings having ori- 20 fices 64 for the wheel axles. The pony truck has a swinging bolster 65 supporting a center pin and supported on a cross tie 66, being connected thereto by the links 67. 68 is a safety strap, and 69 the truck pedestals 25 resting in boxings 61.

Referring to Fig. 6, 70 are the driving rods, 71, 72 and 73, the three parts of the main rods, 74 the straps (stub-ended) holding the brass boxings 75, 76 are the keys se- 30 curing the boxings and 77 are the oil cups.

78 are the driving wheels (see Fig. 3) having the usual wrist pins 79 for the brass boxings of the main rods, and 80 for those of the pitman rods, 81 being washers be- 35 tween the rods and 82 being taps to retain the rods on the pins.

83 are the forward running wheels.

84 is the lever for moving the long rod 85 which operates vertical rods 86 to open and 40 close the steam cocks 87 to let out the exhaust and thus expedite the starting of the engines.

The rear ends of the engines 30 may be 45 provided with a steam protector 109 (Fig. 11) between the slides 89 which guide the cross heads 90.

91 are the piston rods and 92 are exhaust steam gages.

93 is a front guide in line with and guid- 50 ing the piston rod of each engine. The guide is provided with a cock for exhausting steam.

The piston rods 91 pass through the steam protectors 109 into pistons 110 which are 55 provided with bands of metal 111 and suitable packing to insure a steam tight fit. The heads 88 and 89 of the cylinders are secured by bolts as usual.

On axle 64 are mounted eccentric disks 60 94 each connected by a rod 95 to the link 96, there being two disks and rods connected to each link for each engine. In the cab is a lever 97 which shifts the long reversing rod 98 and through it raises and lowers the arms 65 100 mounted on a rocking-cross rod 99 which

serves as a fulcrum, the movement of the arms 100 raising and lowering vertical reversing rods 101 connected to the links 96, thus raising and lowering said links in response to the movement of the lever 97 in 70 the cab. The movement of the links alters the relative adjustment of the eccentric disks.

102 are two part adjustable link blocks joined by a bolt and mounted in links 96. 75 The movement of the links 96 operates crank arms 103 connected to the link blocks and these in turn move shifting rods 104 and through them the valves 105, controlling the steam ports 106 and 107.

108 is a port through which the steam ex- 80 hausts. Thus the eccentric disks are controlled with respect to the steam ports by means of the lever 97 in the cab.

The boiler has two domes and two simu- 85 taneously operating throttles which through a rod start the engines. There are several sets of running gear frames for each boiler and each frame has its pair of engines, one on each side. There is a rod and pitman for 90 the wrist pins for the drive wheels, so the link movements (shown in Fig. 6) will run the engines on each side of the boiler.

In Fig. 4 are shown the cross rod to raise 95 or lower the link, so that the link block will work the valve rod to work the valve in the steam chest so the pressure of the steam will work the piston in its running position.

The boiler rests on a plurality of arches; 100 each in two parts; each part carrying an engine mechanism for its side of the boiler. The boiler rests on braces carried by several sets of running frames, the frames resting on boxings, the boxings on axles, the axles borne by the wheels of the locomotive. 105

The exhaust passes through a nozzle spark dropper pipe above the stack to prevent back draft of sparks and cinders, the sparks and cinders passing between the stack and the spark dropper pipe, striking the catcher and 110 dropping to the ground.

There are four eccentric disks and rods for two links for each pair of engines, one engine being on each side, of a frame. There may be two or more frames.

Having thus described my invention the following is what I claim as new therein and desire to secure by Letters Patent:

1. In a locomotive, the combination of a single boiler mounted on a plurality of 120 wheeled frames or trucks, a plurality of engine mechanisms for propelling each frame or truck, and means for simultaneously conveying power from the boiler to the engine mechanisms comprising a plurality of steam domes, piping connecting the steam domes directly each with the other, piping connecting the first mentioned piping with each of the several engine mechanisms, and horizontally extending piping connecting each 125 130

unit of the second mentioned piping at a point near to each engine mechanism directly with the piping extending to the other engine mechanisms.

5. 2. In a locomotive, a fire box supporting means comprising paired side engine frames, paired axle boxings vertically movable in each of said frames, posts mounted on the boxings, paired lever rocking-arms, each fulcrumed, at an intermediate point, on a post, dippers hung from the outer ends of said rocking-arms, springs supported by the dippers and bearing beneath parts of the frames, paired links carried by the inner 10 ends of the rocking-arms, and a cross piece supported by the links and adapted to support a fire box.
15. 3. In a locomotive, a fire box supporting

means comprising paired side engine frames, paired axle boxings vertically movable in each of said frames, posts mounted on the boxings, paired lever rocking-arms, each fulcrumed, at an intermediate point, on a post, dippers hung from the outer ends of said rocking-arms, springs supported by the dippers and bearing beneath parts of the frames, and a cross piece supported by the inner ends of the rocking-arms and adapted to support a fire-box.

20. 25. In testimony whereof I affix my signature 30
in presence of two witnesses June 2, 1913.

JAMES EDWARD BENNETT.
